UNITED STATES PATENT OFFICE

ALPHONS O. JAEGER, OF MOUNT LEBANON, PENNSYLVANIA, ASSIGNOR TO THE SELDEN COMPANY, OF PITTSBURGH, PENNSYLVANIA, A CORPORATION OF DELAWARE

MOTOR FUEL

No Drawing

Application filed July 23, 1931. Serial No. 552,798.

This invention relates to motor fuels and more particularly to motor fuels containing unsaturated constituents, which tend to form gums such as the so-called cracked gasolines. Cracked gasolines command a premium as motor fuels at the present time owing to their excellent anti-knock qualities. However, they are open to the disadvantage that they form gum and discolor, particularly, when exposed to sunlight. It has been proposed in the past to stabilize unsaturated motor fuels and inhibit or minimize gum formation by the addition of stabilizers, among which, only two have achieved any practical success, namely, anthracene and acid amides of aromatic amines such as acetanilide.

I have found that very effective stabilizers for unsaturated motor fuels are reduced cyclic imides, such as the imidines and hydroxyimides of the general formula

where R is a hydrocarbon, R₁ and R₂ are H, OH, hydrocarbon or where R₁ and R₂ are combined as a single oxygen atom. While the present invention is in no sense limited to any particular imidines or hydroxyimidines, I have found that the cheapest members of this class, namely, phthalimidine and hydroxyphthalimidine are highly effective and because of their extremely low cost compared to other members of the class they are particularly attractive commercially. Substituted imidines in which the hydrogen of the NH group is substituted by other radicals are also highly effective, for example, the ordinary alkyl phthalimidines and hydroxyphthalimidines, such as, methyl or ethyl phthalimidines can be used as can the aryl derivatives, such as, phenyl or benzyl phthalimidine. Hydroxyalkyl compounds such as methanol or ethanol phthalimidines are likewise effective. Similarly, the imidines and hydroxyimidines of naphthalic

anhydride and their substitution products may be employed as well as similar succinimidines and hydroxysuccinimidines. In fact the present invention is generally applicable to imidines and hydroxyimidines from polycarboxylic acids, both aromatic and aliphatic. 15

It is sometimes desirable to prevent the formation of acid in motor fuels by adding small amounts of the base as an antacid. Examples of such bases are amines, particularly aromatic amines, aniline, toluidine, and the like.

The invention will be described in greater detail in connection with the following specific examples, which illustrate typical motor fuels falling within the scope of the present invention. 65

Example 1

2-4 pounds of phthalimidine

are mixed with 100 barrels of cracked gasoline to yield a highly stabilized motor fuel of excellent quality.

Example 2

2-5 pounds of hydroxypyphthalamidine

are added to 100 barrels of cracked gasoline, producing a thoroughly stabilized motor fuel.

Example 3

3-6 pounds naphthalimidine

Example 8

2-5 pounds of ethanol phthalimidine

5

70

75

are added to 100 barrels of cracked gasoline line to obtain a stabilized motor fuel.

or ethanol hydroxyphthalimidine

Example 4

3-6 pounds succinimidine

15

89

85

20 or hydroxysuccinimidine

25

93

are added to 100 barrels of cracked gasoline line to obtain a stabilized motor fuel.

30

Example 5

4-6 pounds of methyl or ethyl naphthalimidine or hydroxynaphthalimidine and aniline are added to 100 barrels of cracked gasoline to produce a stabilized motor fuel.

35

Example 6

2-5 pounds of ethylphthalimidine

40

105

45 or ethyl hydroxyphthalimidine

50

110

are added to 100 barrels of cracked gasoline line to produce a stabilized motor fuel.

55

Example 7

2-6 pounds of methanol phthalimidine

60

115

are added to 100 barrels of cracked gasoline line to produce a stabilized motor fuel.

are added to 100 barrels of cracked gasoline line to produce a stabilized motor fuel.

Example 9

2-5 pounds of phthalimidine or hydroxyphthalimidine and 6 pounds of aniline or toluidine are added to 100 barrels of cracked gasoline forming a well stabilized motor fuel.

In the examples the amount of stabilizers is a fraction of 1%. In general, this is sufficient to obtain satisfactory stabilization.

Larger amounts of stabilizers, of course, do no harm, but it is normally unnecessary to use them in quantities larger than 1%.

In the claims the expression "cyclic imide substance" includes not only the imides of polycarboxylic acids, but the hydrogenated and substitution products of the imidines and hydroxyimidines.

What is claimed as new is:

1. A cracked motor fuel containing a cyclic imide substance in an amount sufficient to inhibit gum formation.

2. A motor fuel containing unsaturated gum forming constituents and a cyclic imide substance in an amount sufficient to inhibit gum formation.

3. A cracked motor fuel containing a phthalimidine substance in an amount sufficient to inhibit gum formation.

4. A motor fuel containing unsaturated gum forming constituents and a phthalimidine substance in an amount sufficient to inhibit gum formation.

5. A cracked motor fuel containing phthalimidine in an amount sufficient to inhibit gum formation.

6. A motor fuel containing unsaturated gum forming constituents and phthalimidine in an amount sufficient to inhibit gum formation.

7. A cracked motor fuel containing hydroxyphthalimidine in an amount sufficient to inhibit gum formation.

8. A motor fuel containing unsaturated constituents and oxyphthalimidine in an amount sufficient to inhibit gum formation.

9. A cracked motor fuel containing an N-

125

120

130

- substituted phthalimidine in an amount sufficient to inhibit gum formation.
10. A cracked motor fuel containing an N-substituted hydroxyphthalimidine in an amount sufficient to inhibit gum formation.
11. A cracked motor fuel containing a hydroxyalkyl N-substituted phthalimidine in an amount sufficient to inhibit gum formation.
- 10 12. A cracked motor fuel containing a hydroxyalkyl N-substituted hydroxyphthalimidine in an amount sufficient to inhibit gum formation.
- 15 13. A cracked motor fuel containing an aryl phthalimidine in an amount sufficient to inhibit gum formation.
14. A cracked motor fuel containing an aryl hydroxyphthalimidine in an amount sufficient to inhibit gum formation.
- 20 15. A motor fuel according to claim 1, in which the amount of the imidine substance does not exceed 1%.
16. A motor fuel according to claim 6, in which the amount of the phthalimidine does not exceed 1%.
- 25 17. A motor fuel according to claim 8, in which the amount of hydroxyphthalimidine does not exceed 1%.
18. A motor fuel according to claim 1, in which an antacid is present in addition to the imidine substance.
- 30 19. A motor fuel according to claim 6, in which an antacid is present in addition to the phthalimidine.
- 35 20. A motor fuel according to claim 8, in which an antacid is present in addition to the hydroxyphthalimidine.
- 40 21. A cracked motor fuel containing a material selected from a class consisting of phthalimidine, hydroxyphthalimidine, naphthalimidine, hydroxynaphthalimidine, succinimidine, hydroxysuccinimidine, ethylphthalimidine, ethylhydroxyphthalimidine, methanolphthalimidine and ethanolphthalimidine, the amount of the imidine substance being sufficient to inhibit gum formation and being approximately within the ratio of two pounds of imidine substance to 100 barrels of cracked gasoline to 1% of phthalimidine substance.
- 50 Signed at Pittsburgh, Pennsylvania, this 22nd day of July, 1931.

ALPHONS O. JAEGER.
